JOINT AND CONNECTER

Thomas C. Green, United States Marine Corps

Application September 14, 1936, Serial No. 100,689

3 Claims. (Cl. 285—47)

(Granted under the act of March 3, 1883, as amended April 30, 1928; 370 O. G. 757)

My invention relates to an electrically continuous, substantially fluid impervious joint and to a connector for connecting together an electrically conductive element provided with an opening and an electrically conductive casing element and for insuring electrical continuity and continuity of passage therebetween.

In order to effectively shield extraneous apparatus against electro-magnetic and electro-static disturbances caused by ignition circuits of internal combustion engines, it is essential that the circuit be completely enveloped by a metallic surface; that the enveloping metallic surface be grounded at its ends and at suitable intervals therebetween; and that the enveloping metallic surface be electrically continuous throughout its length. Failure of the enveloping metallic surface to properly and effectively shield against the deleterious disturbances generated by the ignition circuits is caused principally by lack of electrical continuity along the enveloping metallic surface, or an increase in resistance of the enveloping metallic surface over that at which optimum shielding is obtained. This lack of electrical continuity or increase of resistance takes place at the connectors and joints forming a part of the enveloping metallic surface. As long as the contacting surfaces of the connectors and joints are in intimate metallic contact and remain free from dirt, oil, gasoline, or other extraneous matter, the enveloping metallic surface will effectively shield. If, however, the contacting surfaces of the connectors and joints are not in intimate metallic contact, or do not remain free from extraneous matter, there will be a lack of electrical continuity or an increase of resistance through the connectors and joints with attendant interruption or mal-functioning in the shielding properties of the enveloping metallic surface.

Shielding failure in aircraft shielding assemblies is commonly caused by the through connector which connects a junction box adjacent the opening therein with a shielding conduit or by the joint which this connector makes with the wall or partition of the junction box adjacent the opening or outlet therein, since both connector and joint fail to perform their primary function of providing electrical continuity between the junction box and shielding conduit.

In the prior art shielding assemblies the joint at the opening or outlet in the junction box is formed by causing the sides of the junction box to contact, respectively, with a flange at one end of an externally threaded connector body and with a face of a nut in threaded engagement with said body. Sole reliance for electrical continuity at this joint is placed upon the contact made by the flange and nut with the sides of the junction box adjacent the opening therein. As it is general practice to paint junction boxes before in-

stalling the through connector in the outlet hole thereof, electrical contact between the sides of the junction box and the through connector is dependent upon some part of the connector rubbing away sufficient paint during installation to make contact with the metal beneath. During installation the nut is usually the connector part which is rotated in order to secure the connector tightly in place and consequently when fortuitous electrical contact occurs between the connector and the sides of the junction box it is usually between a face of the nut and the outside wall of the junction box, where this mutual contact is most subject to destruction by oil or corrosion due to moisture.

With the foregoing preliminary discussion in view, it is an object of my invention to provide a joint wherein the juncture between the joint parts is sealed against the exterior whereby electrical continuity through the joint is insured.

It is another object of my invention to provide an electrically continuous joint wherein the juncture between the joint parts is maintained by direct and intimate metallic contact, the said juncture being sealed against the exterior to thus preserve unaltered the resistance through the joint.

It is another and further object of my invention to provide a connector for connecting an electrically conductive casing element to an electrically conductive element having an opening, and for insuring electrical continuity and continuity of passage therebetween.

It is another and still further object of my invention to provide a connector for connecting an electrically conductive casing element to an electrically conductive element having an opening, and for insuring electrical continuity and continuity of passage therebetween, wherein the juncture between the connector parts and the juncture between one end of the connector and the electrically conductive element adjacent the opening therein are maintained by direct and intimate metallic contact, the said junctures being sealed against the exterior to thus preserve unaltered the resistance therethrough and to insure electrical continuity from one electrically conductive element to the other.

Other objects and many of the attendant advantages of this invention will be readily appreciated as the same becomes better understood by reference to the following description when considered in connection with the accompanying drawing wherein:

Figure 1 is an assembled view in section of my connector and the joint which one end of the connector makes with a wall adjacent an opening therein;

Figures 2 and 3 are, respectively, a view in sec-

tion and a view in end elevation of the female connector part or member; and

Figures 4 and 5 are, respectively, a view in end elevation and a view in section of the nut adapted for threaded engagement with the female connector part.

My invention seeks to provide a connector and a joint between one end thereof and an electrically conductive element provided with an opening which are not only electrically continuous but whose resistance is preserved substantially unaltered. To accomplish the foregoing I maintain a direct and intimate metallic contact between the male and female connector parts by causing a wedging action between their contacting surfaces through the medium of a suitable coupling means, the contact or juncture between the connector parts occurring within the confines of a compressible fluid impervious means to thus effectively seal the juncture against the connector exterior. The joint is formed by providing the female connector part at one end thereof with a plurality of projections which are forced into contact with the electrically conductive element adjacent the opening therein, the area of contact therebetween being sealed against the joint exterior.

The joint and connector of my invention are intended primarily for use with the shielding of aircraft ignition circuits and are so described in their specific application hereinafter. It is to be emphasized, however, that the joint and connector of my invention are not restricted to the aforementioned use but may be used wherever and whenever an electrically continuous joint and connector are desired.

Turning now to the drawing there is shown in Figure 1 in assembled relation a connector identified in general by the numeral 1 for connecting together the shielding conduit 2 and apertured wall 3 of a junction box and for permitting the passage of the ignition cable 4 from the conduit into the junction box, the said connector including a female connector part 5, a male connector part 6, a deformable and compressible gasket 7 which serves as a fluid impervious sealing means and is interposed between the connector parts and a coupling 8 for maintaining a direct and intimate metallic contact between the connector parts and for causing the connector parts to compress the gasket 7 whereby to seal the surfaces of contact between the connector parts against the connector exterior.

The female and male connector parts or bodies 5 and 6 are apertured at 9 and 10, respectively, to permit the passage of the ignition cable 4 from the shielding conduit 2 into the junction box. In addition one end of the female connector part 5 is provided with a conical recessed surface 11 with which a corresponding conical surface 12 of the male connector part 6 is adapted to contact, to thereby insure electrical continuity through the connector. While the contacting surfaces of the male and female connector parts are shown as conical in shape, I do not desire to be restricted thereto since other inclined contact surfaces may be employed within the purview of my invention and will readily suggest themselves to those skilled in the art, hemispherical surfaces and pyramidal surfaces being illustrative but not restrictive of such other inclined surfaces.

The female and male connector parts 5 and 6 are furthermore provided with bearing faces 13 and 14, respectively, extending outwardly of the

connector from adjacent the outermost edges of the conical or inclined surfaces 11 and 12, these bearing faces being adapted to abut against the sides of the deformable, fluid impervious gasket 7 interposed therebetween to compress the same and thereby seal the surfaces of contact 11 and 12 between the connector parts or bodies 5 and 6 against the connector exterior. The gasket 7 is preferably, although not necessarily, annular in shape and is placed about and supported by the cylindrical portion 15 of the male connector part 6. This gasket which serves as a sealing means may be fabricated from synthetic rubber or any other suitable material so long as the material chosen is fluid impervious, will withstand the weather and be reasonably resistant to fluids such as, for example, gasoline, oil, and water.

In order to insure a direct and intimate metallic contact between the contacting surfaces 11 and 12 of the connector parts and a compression of the gasket 7, the male and female connector parts have been provided with a flange 16 and screw threads 17, respectively, which are adapted to engage a complementary flange 16' and internal screw threads 17' of a coupling sleeve or nut 8. Portions 18 of the coupling sleeve or nut 8 are hexagonally or otherwise shaped to permit the use of a wrench for tightening purposes. The coupling sleeve or nut 8 in addition to holding the contact surfaces 11 and 12 of the connector parts in intimate and direct metallic contact and causing a compression of the gasket 7, serves also to furnish some protection to the gasket 7 and to provide a secondary electrically conductive path between the male and female parts of the connector.

The male connector part 6 is recessed or rabbeted at 19 to provide inner and outer walls 20 and 21, respectively, between which the shielding conduit 2 is received. Since in this embodiment of my invention the male and female connector parts 5 and 6 and the coupling sleeve 8 are made of brass, bronze, or other alloys, or metals, which can be readily soldered, the male connector part 45 is attached to its shielding conduit 2 of similar material by sweating the outer wall 21 with solder to the outside of the conduit. The inner wall 20 of the male connector part 6 in this case serves to support the inside of the shielding conduit 2 and to prevent sharp edges thereof from causing damage to the ignition cable 4.

Where, however, the connector parts are made of an aluminum alloy or metal which cannot be conveniently soldered to a shielding conduit of similar material, I may employ an alternate mode of connection which consists in swaging the outer sleeve 21 inwardly around the shielding conduit 2 and the inner sleeve 20 outwardly against the shielding conduit 2 to thus provide a mechanically secure and electrically continuous engagement between the male connector part and the shielding conduit.

The threaded body portion of the female connector part 5 is provided at another end thereof with a plurality of circumferentially spaced projections, or splines 22 and a flange 23, the said projections being forced into the wall 3 of the junction box adjacent the opening therein and being in direct and intimate electrical contact therewith. A fluid impervious gasket 24 is interposed between the flange 23 and one side of the wall 3 of the junction box and a second gasket 25 placed adjacent the opening in the wall 3 and on the other side thereof, these gaskets being

compressed and held in fluid impervious engagement with the sides of the wall 3 by means of a nut 26. Both gaskets are fabricated in a manner similar to that of the gasket 7. The nut 26 has a portion of the inner face cut away at 27 to provide space for the projections or splines and/or the metal they displace, while permitting a tight fit between the inner face of the nut and the fluid impervious gasket 25 and the use of the connector regardless of the thickness of the wall or partition 3 through which it passes. A tight fit between the wall 3 of the junction box, on the one hand, and the gaskets 24 and 25, the flange 23 and the nut 26, on the other hand, is essential in order to effectively seal the area of contact between the projections 22 and the junction box wall 3 against the exterior and hence against the introduction of any extraneous matter such as, for example, oil and water. It is to be emphasized, however, that the washers or gaskets 24 and 25 need not be employed since a joint which is substantially and effectively sealed against the exterior may be obtained by causing the inner faces of the flange 23 and the nut 26 to intimately contact the faces of the wall 3.

In use the female connector part is placed through the opening in the wall 3 of the junction box and the nut 26 threaded thereon and tightened with or without the interpositioning of gaskets 24 and 25. The tightening of the nut causes the projection 22 to cut into the wall 3 of the junction box adjacent the opening therein and thus to provide a direct and intimate electrical contact therewith. The tightening of the nut 26 serves also to provide a substantially fluid impervious juncture between the wall 3, on the one hand, and the flange 23 and nut 26, on the other hand, to thereby seal the area of contact between the wall 3 and the projections 22 against the exterior and thereby insure electrical continuity at this joint. The nut 8 is now assembled over the male connector part 6 and the fluid impervious gasket 7 placed about the cylindrical portion 15 of the male connector part. The female connector part 5 is then brought into place and the parts secured together by tightening the coupling sleeve 8. As the sleeve or nut 8 is tightened the conical projection on the male connecting part is wedged into the corresponding conical recess of the female connecting part thus providing direct electrical continuity through the connector. Simultaneously with the tightening of the nut or sleeve 8 the sides of the gasket 7 are compressed between the bearing faces 13 and 14 of the connector parts thus sealing within its confines the surfaces of contact 11 and 12 of the connector parts against the introduction of extraneous materials such as gasoline, oil and moisture.

According to the provisions of the patent statutes I have set forth the principle and mode of operation of my invention and have illustrated and described what I now consider to represent its best embodiment. However, I desire to have it understood that within the scope of the appended claims the invention may be practiced otherwise than as specifically illustrated and described.

This invention may be manufactured and used by or for the Government of the United States of America for governmental purposes without payment of royalties thereon or therefor.

I claim:

1. Means for connecting an electrically conductive casing element to an electrically conductive element provided with an opening and for insuring electrical continuity and continuity of passage therebetween, comprising in combination an apertured, electrically conductive body provided with a plurality of spaced projections at one end thereof and a bearing face and inclined, recessed, contact surface at the other end thereof, means for forcing the projections into electrical contact with the electrically conductive element adjacent the opening therein and for sealing the area of contact therebetween against the connector exterior, a second apertured electrically conductive body adapted for connection to said casing element and having a contact surface in electrical contact with that of said first mentioned body and a bearing face, deformable means interposed between the bearing faces of said bodies and adapted to be engaged thereby for sealing the area of contact at the surfaces of said bodies against the connector exterior, and means for holding said bodies in wedging engagement at their surfaces of contact and for causing the bearing faces to abut against the deformable means interposed therebetween.

2. An electrically continuous shielding assembly comprising in combination an electrically conductive casing element, an electrically conductive element provided with an opening and means for connecting said elements together and for insuring electrical continuity and continuity of passage therebetween, said means including an apertured, electrically conductive body provided with projecting means at one end thereof and a contact surface at the other end thereof, means for forcing the projecting means into electrical contact with the electrically conductive element adjacent the opening therein and for sealing the area of contact therebetween against the connector exterior, a second apertured electrically conductive body electrically continuous with said casing element and having a contact surface in contact with that of said first mentioned body, means for sealing the area of contact between said first and second mentioned bodies against the connector exterior, and means for holding said first and second mentioned bodies in engagement.

3. Means for connecting an electrically conductive casing element to an electrically conductive element provided with an opening and for insuring electrical continuity and continuity of passage therebetween, comprising in combination an apertured, electrically conductive body provided with projecting means at one end thereof and a contact surface at the other end thereof, means for forcing the projecting means into electrical contact with the electrically conductive element adjacent the opening therein and for sealing the area of contact therebetween against the connector exterior, a second apertured electrically conductive body adapted for connection to said casing element and having a contact surface in contact with that of said first mentioned body, means for sealing the area of contact between said first and second mentioned bodies against the connector exterior, and means for holding said first and second mentioned bodies in engagement.

THOMAS C. GREEN.
